CLOCK

Joseph F. Punzak, Brooklyn, N. Y., assignor to United Metal Goods Manufacturing Co., Inc., Brooklyn, N. Y., a corporation of New York

Application March 16, 1955, Serial No. 35,078

Term of patent 14 years

(Cl. D42—7)

Fig. 1.

Fig. 2.

Fig. 1 is a perspective view of a clock, showing my new design.

Fig. 2 is an end elevation of Fig. 1 looking from the left.

The characteristic feature of the present design resides in the particular fireplace motif in relation to and association with the clock housing.

I claim:

The ornamental design for a clock, as shown and described.
